UNITED STATES PATENT OFFICE.

HENRY H. SMITH, OF KALAMAZOO, ASSIGNOR OF ONE-HALF TO MARY MOHR KRUSE, OF PORTAGE, MICHIGAN.

TWO-WHEELED VEHICLE.

SPECIFICATION forming part of Letters Patent No. 376,992, dated January 24, 1888.

Application filed October 13, 1887. Serial No. 252,246. (No model.)

To all whom it may concern:

Be it known that I, HENRY H. SMITH, a citizen of the United States, residing at Kalamazoo, county of Kalamazoo, State of Michigan, have invented a new and useful Two-Wheeled Vehicle, of which the following is a specification.

This invention relates to that class of two-wheeled vehicles the seat-bars or body of which is fulcrumed at the forward end and suspended over the axle at the rear end; and it has for its object a construction and association of parts, substantially as below set forth and claimed.

15 In the drawings forming a part of this specification, Figure 1 is a side elevation with one wheel removed; Fig. 2, an enlarged perspective of lettered details in Fig. 1; Fig. 3, a rear elevation of lettered details enlarged, with 20 parts in section near the hanger *r*. Figs. 4 and 5 are broken details, below described.

Referring to the lettered parts of the drawings, *A* is the axle, *B* the thills, and *D* the seat-bar or body fulcrumed at the forward end, 25 all substantially as disclosed in the prior state of the art.

Heretofore the curved rear end of the thills has been provided with the ordinary braces in a similar relation to the thills as the 30 combined braces and spring-supports *a* here shown. In the present instance the supports *a* are longer, or, more properly, enlarged both in size and length, and, while performing the old function of a brace, are especially adapted to support the springs of the 35 vehicle. (See Figs. 1 and 2.) These supports *a* (here shown vertically edgewise and rigid) may be of flat elastic metal, if preferred, so long as they serve the combined office of a 40 brace and spring-support.

Of course it will be understood that the vehicle on both sides is like the side here illustrated. At *c* is shown a spring like a letter *V*, having one branch extended. The shorter 45 branch is attached at *v* to the spring-support *a*, and to the free end of the upper elongated branch a hanger, *r*, is pivotally attached. The lower end of this hanger is pivotally attached in any suitable manner to the 50 body or seat-bars *D*. As here shown, it is attached to the bar *C*, which adjustably engages the notches of the plate *u*. By this means the height of the body may be changed. The leverage of the body *D* on the springs *c*

may be changed by loosening the clips at *v* 55 and attaching the springs *c* to the support *a* at a point forward or in the rear of the point here shown. So far as the spring *c* is concerned, any suitable spring may be employed, supported by the combined brace and spring- 60 support *a*.

An important feature of this invention rests in the fact that the effect of the springs can be dispensed with and the cart be made rigid, so to speak, when desiring to speed the horse. 65 I effect this as follows: Through the lower part of the hanger is a round hole having a communicating extension or recess, *S*, Fig. 4, and a like hole is made through the spring-support *a*, registering with the hole in the 70 hanger, as at *S*, Fig. 5. A key or bolt, *i*, is inserted into the holes *S* *S*, said key having lugs *e* *e*, and after the key is inserted it is given a half-turn, and by means of these lugs *e* the said key is locked from lateral displacement. By this means the seat-bars or body is rigidly supported—that is, the elastic effect of the springs is dispensed with, and the vehicle is adapted for speeding purposes. 75

Having thus described my invention, what I 80 claim is—

1. The combination of the thills having the combined braces and spring-supports, a body or seat-bars fulcrumed at the forward end, and springs mounted upon and attached to 85 said braces and suspending or supporting said body, substantially as set forth.

2. The combination of the vehicle-body fulcrumed at the forward end, the thills having the spring-support, the springs having the extended end, the short end being mounted upon and attached to said support, and hangers suspending the body from the extended ends of the springs, substantially as set forth. 90

3. In combination, a fulcrumed vehicle-body, the thills having the combined braces and spring-supports, springs, hangers suspending the body from said springs, and bolts or keys adapted to lock the hangers to the braces, whereby the effect of the springs is 95 dispensed with, substantially as set forth.

In testimony of the foregoing I have hereunto subscribed my name in presence of two witnesses.

HENRY H. SMITH.
